UNITED STATES PATENT OFFICE.

FRANK RUDOLPH KURETICH, OF SUNNYSIDE, UTAH.

DOOR-LATCH.

1,319,011.

Specification of Letters Patent.

Patented Oct. 14, 1919.

Application filed October 11, 1916; Serial No. 125,053. Renewed June 24, 1919. Serial No. 308,428.

To all whom it may concern:

Be it known that I, FRANK RUDOLPH KURETICH, a citizen of the United States, residing at Sunnyside, in the county of Carbon and State of Utah, have invented new and useful Improvements in Door-Latches, of which the following is a specification.

This invention relates to door fasteners and more particularly to that class generally known as twin door latches.

The primary object of the invention resides in the production of a latch of this character wherein the operating handle of the latch is so constructed as to facilitate the same in performing a locking action of the latch when the same is either locked or unlocked.

In carrying out the present invention I contemplate forming the door plate with a slot in which is slidably mounted the said operating handle, and connected with the latter is the latch operating mechanism whereby upon the movement of said handle to one extreme end of the slot will permit 25 of a partial rotation thereof and perform the locking action of the handle, which in turn locks the latch bolts against movement.

With the above and other objects in view the improvement resides in the construction, 30 combination and arrangement of parts set forth in the following specification and falling within the scope of the appended claims.

In the drawing:

Figure 1 is a vertical sectional view taken 35 through a door showing the latch applied thereto and in a locking position.

Fig. 2 is a perspective view of the latch removed from the door,

Fig. 3 is a detail sectional view clearly 40 illustrating the means for locking the latch bolts against movement, and

Fig. 4 is a detail perspective view of the operating handle.

In carrying out the present invention 5 denotes my improved twin latch and illustrated as applied to a door A swingingly connected in the door casing B.

This twin door latch embodies a door plate 6 secured to the inner face of the door A 50 through the medium of fasteners 7 and positioning the door plate in a vertical plane with respect to the door, while formed centrally in the door plate is a horizontally extending elongated slot 8 terminating at its 55 opposite ends in enlarged sockets 9. The purpose of such sockets will be hereinafter

more fully explained as the description of the invention is proceeded with. Mounted upon this plate 6 for vertical sliding movement and adapted to operate in the guide-ways 10 secured to said plate, is a pair of latch bolts 11 and 12 respectively. Suitable mechanism, indicated generally by the character 13, is employed for simultaneously re-tracting or extending the oppositely dis-60 posed latch bolts 11 and 12 and to this end such mechanism embodies a pair of bell crank levers 14 and 15 fulcrumed, as at 16, on the door plate 6 to opposite sides of the slot 8 adapting the bell crank levers for 65 vertical swinging movement. The said bell crank levers 14 and 15 are terminally provided at their outer ends with a transverse slot 17 through which passes the pivot 18, thus pivotally connecting each of the latch 70 bolts 11 and 12 in the slot 17 of the bell crank levers. Pivotally connected to the inner extremities 19 of the bell crank levers through the medium of the pivot 20 is a pair of links 21 and 22 respectively. The meet-75 ing or inner ends of the links overlap one another and loosely receive the shank 23 of the operating handle 24. This shank 23 pro-trudes through the slot 8 of the door plate 6 and is prevented from any accidental dis-80 placement from said slot by means of any suitable fastening device, but for the purpose of illustration I have shown such device as constituting a disk. Thus it will be seen that by this arrangement the operating han-85 dle 24 is adapted to slide in the slot 8 in a horizontal direction with respect to the door plate 6 and upon movement of the handle in the direction indicated by the arrow in Fig. 2 of the drawing, will draw the links 21 90 and 22 together and thus rock the bell crank levers 14 and 15 upon the fulcrum 16, and in turn simultaneously operate the latch bolts 11 and 12 in door locking position, ex-95 tending the same in the sockets 25 and 26 connected in the respective upper and lower 100 portions C and D of the door casing B. The operating handle 24 when the latch bolts are in locked position, disposes its shank 23 in the forwardmost socket 9 of the slot 8 105 and by the enlargement of this socket pre-sents at the point of formation of the same with the contracted slot 8 horizontal shoul-ders 27. The shank 23 of the operating handle being provided with opposite flat-110 tened side faces 28, will, upon revolving the operating handle 24 dispose the flattened

side faces crosswise of the slot and cause the said flattened side faces to abut with the horizontal shoulders 27 of the socket, establishing a locking action of the latch bolts. 5
On the other hand when the operating handle 24 is moved to the opposite extremity of the slot 8 and the shank 23 is disposed in the rearmost socket 9 of the slot, upon a slight revolution of the operating handle will 10 cause the flattened side faces 28 of the shank to be disposed crosswise of the slot 8 and causing the said faces to abut with the horizontal shoulders 27 and prevent the latch bolts being moved to locked position.

15 From the above description, taken in connection with the accompanying drawing, the simplicity of the device, as well as the advantages thereof will, it is thought, be perfectly apparent to those skilled in the art 20 to which such invention appertains without further detailed description.

Having thus described the invention, what I claim is:

1. In a twin door latch, the combination 25 with a door plate provided with a horizontally disposed slot at a point intermediate the top and bottom edges of the plate and terminating at its opposite terminals in enlarged sockets presenting shoulders, a pair 30 of oppositely disposed latch bolts slidably mounted on said plate, a bell crank lever pivotally mounted on the plate to opposite sides of the slot and having pivotal connection at one end with each of the latch bolts, an operating handle slidably mounted in said slot, and a link attached to the opposite ends of 35 the bell crank levers and said operating handle for imparting to the levers a rocking movement upon the adjustment of the operating handle in said slot.

40 2. In a twin door latch, the combination with a door plate provided with a horizontally disposed slot at a point intermediate the top and bottom edges of the plate and

Copies of this patent may be obtained for five cents each, by addressing the "Commissioner of Patents, Washington, D. C."

terminating at its opposite terminals in enlarged sockets presenting shoulders, a pair of oppositely disposed latch bolts slidably mounted on said plate, a bell crank lever pivotally mounted on the plate to opposite sides of the slot and having pivotal connection at one end with each of the latch bolts, an operating handle slidably mounted in said slot, a link connection between the opposite ends of the bell crank levers and said operating handle for imparting to the levers a rocking movement upon the adjustment of the operating handle in said slot, and means formed integral with the operating handle which co-acts with the shoulders upon the rotation of the operating handle to hold the bell crank levers against rocking movement.

3. In a twin door latch, the combination with a door plate provided with a horizontally disposed slot at a point intermediate the top and bottom edges of the plate, and terminating at its opposite terminals in enlarged sockets presenting shoulders, a pair of oppositely disposed latch bolts slidably mounted on said plate, a bell crank lever pivotally mounted on the plate to opposite sides of the slot and having pivotal connection at one end with each of the latch bolts, an operating handle slidably mounted in said slot, and a link connection between the opposite ends of the bell crank levers and said operating handle, the operating handle being loosely mounted in the overlapping extremities of said links, a squared shank formed integral with said operating handle and working in the slot of the plate, said shank, upon the rotation of the operating handle in the links, adapted to abut with said shoulders to hold the bell crank levers against rocking movement.

85 In testimony whereof I affix my signature.

FRANK RUDOLPH KURETICH.
